C. LEDIN

SWITCH LOCK

Filed Jan. 20, 1923

Attorneys

UNITED STATES PATENT OFFICE.

CHARLES LEDIN, OF STAMFORD, CONNECTICUT, ASSIGNOR TO THE YALE & TOWNE MANUFACTURING COMPANY, OF STAMFORD, CONNECTICUT.

SWITCH LOCK.

Application filed January 20, 1923. Serial No. 613,934.

To all whom it may concern:

Be it known that I, CHARLES LEDIN, a citizen of the United States, and a resident of Stamford, in the county of Fairfield and State of Connecticut, have invented certain new and useful Improvements in Switch Locks; and I do hereby declare the following to be a full, clear, and exact description of the invention, such as will enable others skilled in the art to which it appertains to make and use the same.

This invention relates to improvements in switch locks, and particularly to key-controlled locking means for an electric snap switch,—one object of the invention being to so construct switch locking and operating devices that simple and efficient means shall be provided between the rotatable member of a cylinder lock and the movable member or members of the switch, which will permit the key to be turned backwardly for removal after having been turned in the other direction to operate the switch, without disturbing the settings of the switch points.

With this and other objects in view, the invention consists in certain novel features of construction and combinations of parts as hereinafter set forth and pointed out in the claims.

In the accompanying drawings,—

Figure 1 is a sectional view, partly in elevation, showing an embodiment of my invention.

Figure 2 is a front view.

Figure 3 is a rear view.

Figure 4 is a rear view showing the casing and illustrating the manner of securing the shell of a cylinder lock therein, and

Figures 5, 6, 7 and 8 are detail views.

In the drawings, a base block is shown at 1 and carries an electrical snap switch of any preferred construction located at 2. The details of the switch contact parts do not constitute any part of my present invention and they need not be specifically shown and described herein. Suffice it to say that the stem of an ordinary electric snap switch is shown at 3 and this is provided with a threaded shank 4 to receive an internally threaded sleeve or bushing 5, which is held against turning by a distorted spring washer 6^a interposed between one end of said sleeve or bushing and the switch stem 3.

The sleeve or bushing 5 is serrated on its

exterior to form an annular series of longitudinally extending teeth or ribs 6 and it passes through a centrally located hole 7 in a disk 8,—the wall of said hole being formed with longitudinally extending grooves 9, in which the teeth or ribs 6 mesh and thus the disk 8 is connected with the bushing in such manner that it may impart rotary motion to the switch stem and be capable of movement in a direction relatively to the axis of said stem. A spring 9^a is located between the switch structure 2 and the disk 8 and tends normally to press the disk forwardly.

A casing 10 encloses the mechanism of the device and the base portion of this casing is enlarged as at 10^a and provided with inwardly projecting lugs 11 for the accommodation of fastening bolts 12. This portion of the casing may be lined with paper 13, and the fastening devices may be segregated from the switch and portions of its operating means by partitions 14 of paper or other insulating material. The enlarged portions of the casing may be provided with holes 15 to permit access to the fastening bolts 12, but these holes are normally covered by a ring 16 of fiber or other suitable material. The fiber ring is provided with a recess 17 which may be caused to align with the holes 15 to permit access to the fastening bolts. The fiber ring is so connected with the part which is rotatable by operation of a lock, that it will rotate with such part when the lock is operated with the use of a proper key, and thus the notch or recess 17 will be brought into alignment with one or the other of the holes 15 in the casing base 10^a only when the mechanism is operated with the use of a key.

The fiber ring 16 is provided with an annular flange 16^a which enters the smaller part of the casing and surrounds the disk 8, with which latter it is connected by means of a pin 18 entering an elongated slot 19 in said flange 16^a.

A disk of insulating material, preferably of hard fiber is shown at 20 and secured by screws 21 to the disk 8. The disk 20 is provided with opposite recesses which form inclined faces 22 and shoulders 23, the latter being disposed parallel with the axis of the disk.

A cylinder lock 24 is located in the front end portion of the casing 10 and is provided

95

2
with lugs or ears 25 through which screws 26 pass and enter lugs 27 rigid with the casing. The front end portion of the casing 10 is formed with a suitable opening for the accommodation of the forward end of the cylinder lock and the plug 28 of said lock is provided at its rear or inner end with two pins or screws 29 located at diametrically opposite sides of the center of said plug and 10 adapted to co-operate, respectively, with the shoulder 23 of the disk 20.

With the construction and arrangement of the parts above described, it will be understood that when a proper key is inserted 15 into the plug of the lock and turned so as to turn said plug, the cooperation of the pins 29 with the shoulders 23 of the fiber block 20 will cause said block and the block 8 to turn and impart rotary motion, through the sleeve 5 to the stem of the switch and thus operate the latter. When the key is turned backwardly to permit its removal, the backward turning of the lock plug will cause the pins 29 to ride on the cam or inclined faces 25 22 and thus force the blocks 20 and 8 backwardly against the resistance of the spring 9 and without imparting any movement to the switch members. Thus it will be seen that the key may be withdrawn from the 20 lock without disturbing the positions of the contact points of the switch to which said points may have been set by the initial operation of the lock.

Having fully described my invention what 35 I claim as new and desire to secure by Letters Patent, is:

1. In a lock controlled switch, the combination of switch operating means, a revolvable member operatively associated therewith and capable also of longitudinal movement, a spring pressing said revolvable member forwardly, a key operated member, and cam devices between said revolvable member and key operated member.

46 2. In a lock controlled switch, the combination of switch operating means, a member mounted to rotate with and have longitudinal movement relatively to said switch operating means, a spring resisting backward movement of said member, said member provided with a part having a notch having one of its walls inclined and its other wall substantially parallel with the axis of said member, and a key operated member operatively 50 associated with the notched part of the first mentioned member.

3. In a lock controlled switch, the combination of switch operating means provided with a threaded shank, a bushing on said shank provided with a serrated exterior, a disk having an opening receiving said bushing and provided with serrations to mesh with the serrations of said bushing, whereby said disk may turn with the bushing and move longitudinally thereof, a cam disk secured to the first mentioned disk, a key operated lock having a revolvable member, means carried by the revolvable member of the lock and cooperable with said cam disk, and a spring normally pressing said disks 65 70 forwardly.

4. In a lock controlled switch, the combination of a switch having a stem, a casing, a cam disk rotatable with and longitudinally movable relatively to said stem, a spring normally pressing said disk forwardly, a cylinder lock secured in the forward portion of the casing, and a projection on the plug of said lock to cooperate with said cam disk and rotate the same when 75 turned in one direction and move the same backwardly against the resistance of the spring when turned in the other direction.

5. In a lock controlled switch, the combination with an operating member of the switch and a casing having an enlarged base portion provided with lugs to receive fastening means and with holes in line with said fastening means, of a disk movable in the casing and connected with the operating member of the switch so as to turn the same and to move longitudinally thereof, a spring forcing said disk forwardly, an insulating ring located in the enlarged portion of the casing and normally covering the holes in 90 the latter, said ring having a notch or recess and also provided with a flange encircling said disk and having an elongated slot, a pin projecting from said disk and entering said elongated slot, a cam disk secured 95 to the first mentioned disk, and a cylinder lock secured in the forward portion of the casing and provided with means cooperable 100 with said cam disk.

In testimony whereof, I have signed this 105 specification in the presence of two subscribing witnesses.

CHARLES LEDIN.

Witnesses:

JOHN B. FREYSINGER,
CHARLES A. BERRY.
